To all whom it may concern:

Be it known that we, William Erastus Williams and William Lockerbie Williams, both citizens of the United States and both residing in the city of Los Angeles, in the county of Los Angeles and State of California, have invented a new, original, and ornamental Design for Toy Pistols, of which the following is a specification, reference being had to the accompanying drawing, forming part thereof in which:

We claim:

The ornamental design for a toy pistol, as shown.

WILLIAM ERASTUS WILLIAMS.
WILLIAM LOCKERBIE WILLIAMS.
